Arthur B. Jennings Inventor

UNITED STATES PATENT OFFICE.

ARTHUR B. JENNINGS, OF NEW YORK, N. Y.

AIR COMPRESSOR.

1,421,484.

Specification of Letters Patent. Patented July 4, 1922.

Application filed October 30, 1917. Serial No. 199,386.

To all whom it may concern:

Be it known that I, ARTHUR B. JENNINGS, a citizen of the United States, residing at New York, in the county and State of New 5 York, have invented a new and useful Air Compressor, of which the following is a specification.

This invention relates to air compressors, and especially to that class where the air 10 is compressed by water; and the objects of my invention are to provide an air compressor so constructed that the air will be compressed by flowing water in a stand-pipe, or conduit, to provide means to introduce the air into the flowing water; to provide for the proper division of the stand-pipe, or conduit where the water and air 15 is to flow in one direction and the water alone in the other; to provide means to keep 20 the ascending column of water at a lower level than the descending column; to provide means to strengthen the stand-pipe if desired; to provide suitable means for the extraction of the compressed air from the 25 descending column of water.

The invention is illustrated in the accompanying drawings in which—

Fig. 1, is a sectional elevation of the air compressor constructed in accordance with 30 my invention, a part being shown in full lines, a part diagrammatically, and a part fragmentarily.

Fig. 2, is a transverse section on the line 2—2 of Figure 1 with parts omitted;

Fig. 3, is a sectional view on the line 3—3 of Figure 1, a part being shown fragmentarily;

Fig. 4, is a view similar to Fig. 1, showing a modified form of construction.

Fig. 5, is a transverse section of the same on the line 5—5 of Fig. 4, a part being shown in full lines and a part fragmentarily.

Fig. 6, is a partial transverse section on 45 the line 6—6 of Fig. 4.

Fig. 7 is a view similar to Fig. 1, showing another modified form of construction.

Fig. 8, is a transverse section thereof, on the line 8—8 of Fig. 7, and

Fig. 9, is a transverse section on the line 50 9—9 of Fig. 7.

In the drawings, like letters of reference refer to the same parts in each of the views.

In practice I provide for the production 55 of compressed air in a stand pipe or conduit by utilizing one of considerable height,

and insuring the rapid flow of water through the same.

In Fig. 1, I have shown a stand pipe P preferably of great length divided by a partition T into two longitudinal compartments H, and H^a, the compartment H being the larger in area for purposes hereinafter explained.

To maintain water in the compartment H at a higher level than in the compartment H^a I may employ a pump A of any desired construction, to lift the water from the top I^a in this compartment to the top I in the compartment H. Or the compartment H 70 may be fed from a reservoir B in a manner to maintain the water at a higher level in the compartment H than in the compartment H^a,—a conduit C being provided to permit the water to flow from the compartment H^a so that the flow of water down the compartment H in a rapid manner will be assured. It will be understood, of course, that both the pump A and the reservoir B may be employed simultaneously to ensure 75 a rapid flow of water through the compartments. Air may be introduced into the column of water descending in the compartment H in any desired manner. It may be introduced by inclined pipes G, or by a fan 80 F or by both if desired and it will be understood that the water pumped into the descending column will carry with it considerable air, and the water flowing into the descending column from the reservoir will also 85 carry considerable air.

As the water descends in the column H, pressure will be increased by the weight of water; and the contained air will be forced out by this pressure as well as compressed 90 to a considerable extent thereby. To catch this compressed air I have provided the inverted pockets D, which will be at various heights to allow space for water to flow past them, and are spaced apart so the descending water can flow inwardly between the several pockets thereby more certainly extracting the air; and at the extreme bottom of the pipe where the water turns to ascend in the compartment H^a I mount another 95 pocket E to catch any remaining air contained in the flowing water; and from the pocket E as well as from the pockets D, any number of which may be employed, a pipe J leads to any suitable reservoir for the storage of compressed air as will be clear.

As the pipe P may be of considerable

height I may provide means for reinforcing, or strengthening the bottom. As shown in Fig. 1 the bottom of the pipe P is strengthened with coils of wire W, wound around the pipe in the manner well known.

It will be observed that the partition T as shown in Fig. 2 differs from the partition T^a shown in Fig. 3, as one is angled and the other is not. The angling of the partition may be used in the lower part of the tube to reduce the size of the compartment to allow for the natural contraction of the water in falling, thereby providing means for the more certain extraction of the air.

At the top of the pipe it is desirable to give the descending column a greater area than the ascending column, owing to the fact that this column contains considerable air; but as the column in compartment H continues to descend the air is gradually forced out so that at the bottom of the pipe the partition T^a may occupy the exact centre of the pipe.

Fig. 1 shows my invention as applied to a single pipe. It is evident of course that two or more pipes might be used but it is deemed desirable that the pipes containing the descending water should be greater in area at the top than the pipe or pipes containing the ascending water. Thus, by making the compartment containing air and water larger than the compartment containing only water, provision is made for the volume of air carried in the compartment. It is important, though, that the water in the ascending pipes should be maintained at a lower level than the water in the descending pipe, or pipes—thereby insuring a rapid flow in order to carry the air with the water in its descent, or flow through the pipe, or pipes.

It will thus be seen that I have provided simple and effective means to secure compressed air from flowing water by pressing the air out of the same as the water descends, and by providing for the rapid flow of water through the compression pipes. It will be understood that I may mount a pipe, or pipes of this kind and for this purpose in any desired place, in the shafts of deep mines, or in other suitable locations, and secure the compressed air at any point desired, and for any desired purpose.

In Figs. 4, 5, and 6, I have shown a modified form of construction in which I use a pipe P' oblong in form in cross section, as shown, which may be divided with a partition T' into substantially two compartments H' and H'.

In this construction a plurality of air pockets D' are mounted in the descending column as well as a pocket E' at the bottom. The air gathered by the pockets D' and E' are led to a tank K by pipes J'. I may introduce

additional air in to the descending column with the fan F which may be driven by an external source of power, and I prefer to use too the inclined pipes G to introduce air into the descending column.

Instead of using wire to reinforce the bottom of the pipe P', I may use strengthening strips O as clearly shown on Figures 4 and 5.

In Figures 7, 8, and 9 I have shown another modified form of construction, in which I have provided two pipes P¹ and P² for the descending and assembling columns of water respectively. The tank K is retained and the pipe J.

The operation of compressing air by this construction is substantially the same as that previously described.

As my device largely involves the using of water by returning it the efficiency may be increased by adding soap or oil or both to the water as a method of reducing friction.

I claim:

1. An air compressor comprising a descending, and an ascending column of water, said columns being in communication at both top and bottom, means to introduce air and water into one column, means to maintain the water at a lower level in the other column, and a plurality of pockets arranged at intervals in the descending column adapted to receive air from the flowing water, said pockets being spaced apart and arranged whereby the water may flow inwardly between said pockets.

2. An air compressor comprising compartments adapted to contain ascending and descending columns of water in communication at both top and bottom, means to introduce air and water into one compartment, means to maintain the water at a lower level in the other compartment, and means to extract compressed air from the descending column of water, said means comprising in part a plurality of pockets distributed along the descending compartment, and a pocket located at the juncture between the compartments at the bottom said pockets being in communication with a reservoir.

3. An air compressor comprising a pipe divided into two compartments in communication at top and bottom, means to introduce air and water into one compartment, means to keep the water at a lower level in the other compartment, and means to extract compressed air from the descending column of water, said pipe being divided by a partition angled part of its length, whereby the descending column of water is provided with a smaller compartment at the bottom than at the top.

Dated this 27th day of October 1917.

ARTHUR B. JENNINGS.
